UNITED STATES PATENT OFFICE.

LEVI N. BACHAND, OF CHICAGO, ILLINOIS.

MATTRESS.

SPECIFICATION forming part of Letters Patent No. 758,886, dated May 3, 1904.

Application filed November 25, 1903. Serial No. 182,610. (No model.)

To all whom it may concern:

Be it known that I, LEVI N. BACHAND, a citizen of the United States, residing at Chicago, in the county of Cook and State of Illinois, have invented a certain new and useful Improvement in Mattresses, of which the following is a full, clear, concise, and exact description, reference being had to the accompanying drawings, forming a part of this specification.

10 My invention relates to supporting-mattresses wherein the fabric is of flexible construction and wherein the same assumes a concave or hammock-like form under a superimposed weight.

15 My invention has for its salient features, first, the provision of a mattress wherein the fabric is composed of a plurality of flexible slats or strips, preferably of thin metal yieldingly supported; second, the provision of a 20 supporting-mattress wherein the fabric is composed of flexible slats or strips, the same being located in the direction of the length of the mattress, said slats being flexibly linked together laterally to substantially maintain a 25 prescribed parallel relation between said slats throughout their length.

My invention comprises a mattress fabric adapted to be secured in a frame for use in beds and is of particular service wherein the 30 mattress fabric forms a permanent part of the bed structure, though it is not to be limited to this use.

My invention is also of great service in bed structures that are made collapsible in order 35 to fulfil the utilities of both a couch and bed, in which form of bed the mattress fabric is permanently secured to supporting members, said members forming a part of the bed-frame.

In the preferred construction one group of 40 the component members of the mattress fabric consists of jointless slats or strips, preferably of metal and of sufficient thickness to withstand any tensional strain to which they may be subjected, said slats being also sufficiently 45 thin to render them resilient and flexible in order that they may flex as readily to a superimposed weight bearing upon a restricted

area of the mattress as to a weight engaging a large area. Said slats are desirably arranged parallel with each other and lengthwise of the bed and are preferably separated from each other by a slight clearance. In order to maintain a uniform parallel alignment of the slats between the ends thereof and as in the preferred form between the points of suspension, I desirably unite said slats by suitable links which so connect the slats that the same are permitted to bend and flex without being allowed to spread and permit the bedding or mattress proper to protrude through the fabric of the mattress.

It is desirable that the mattress fabric may be anchored at its points of suspension by means which will permit of a yielding support to the weight sustained. To this end I 65 preferably interpose contractile springs between ends of the slats and supporting parts from which said slats are hung. Said springs afford a yielding action of the slats in the direction of their length, while the slats, owing 70 to their flexible nature, together with the loose link connections between the same, constitute a mattress fabric which is sensitive to pressure received at any point upon its surface and which is readily repaired in case its 75 parts become worn. It is desirable in some embodiments to provide an auxiliary spring-support for said slats which may be located midway between their suspended ends when the mattress fabric is designed for beds of unusual length and when it is desired that said mattresses should be provided with additional resiliency.

I will now describe my invention more fully with reference to the accompanying drawings, 85 showing the preferred embodiment thereof, in which—

Figure 1 is a perspective view of a form of collapsible bed, showing thereon one embodiment of my improved metal mattress. Said 90 view shows the bed in a collapsed or folded position. Fig. 2 is a plan view of the bed shown in Fig. 1 with the folded parts in an open position. Fig. 3 is a transverse detail

sectional view, somewhat enlarged, of a group of slats, showing the flexible link connection and the manner of applying the same.

Like parts are referred to by similar characters of reference throughout the different views.

In the drawings a bed 1 is illustrated which is adapted to be used as a lounge when in the position shown in Fig. 1 and as a bed when in the position shown in Fig. 2. This form of bed is provided with a supporting-mattress embodying the main features of my invention, which is permanently attached to the frame. Longitudinally-disposed slats 2, forming component members of the mattress, are shown suspended at their ends from supporting-bars 3 3 and 4 4, which constitute, respectively, rigid and collapsible members of the bed. Said slats 2 are arranged in parallel relation, with a clearance between each slat, said clearance and the parallel relation of the slats being maintained by flexible connections in the form of wire links 5. The links 5 are desirably arranged in longitudinally-spaced parallel rows extending transversely of the slats 2 and unite the slats together throughout the structure in a manner to afford a torsional or other yielding action of the slats 2 without permitting them to spread and at the same time substantially maintaining their parallel engagement. The strips 2 are provided with alined apertures to accommodate the links 5. In the preferred construction one aperture in each slat is utilized to receive the hook ends of two adjacent links 5, said links connecting, as shown, a centrally-disposed slat 2 with two slats adjacent to the aforesaid slat. Said links 5 are desirably made of wire, the hook end being passed through the apertures in the slats 2 and bent backwardly upon themselves, encircling a portion of the slat and forming a closed hook, as shown in Fig. 3. The body portion of each of the links 5 is preferably straight to enable them to lie flat upon the slats 2 and present to the mattress proper a substantially smooth and unobstructed surface. The hooks of each link 5 are located on the under side of the slats 2, as in the preferred form it is not intended that said hooks should closely embrace the slats 2, but that they should be somewhat enlarged with respect to that portion of the slat which they surround in order to afford play to permit the slats to change their relative positions with respect to each other to effect a flexible connection. This construction supplies a fabric as flexible as a wire mattress and presents the advantage of being more easily repaired in addition to other advantages that are apparent, as shown. Said slats 2 are yieldingly supported at their ends by contractile springs interposed between the ends of the slats 2 and the supporting-bars

3 3 and 4 4, from which said slats 2 are suspended. In the preferred form I provide an individual spiral spring 6 for each of the slats 2 at each end, although this arrangement is not essential to all embodiments of the invention. In the embodiment shown wherein the slats 2 are individually suspended each slat is provided with an aperture through which one end of a contractile spring 6 is passed, while the opposite end of said spring is passed through a like aperture in the supporting members 3 3 and 4 4. The distance between centers of the apertures in the supporting members determines the amount of clearance between the slats 2. In practice the best results have been attained by the use of metallic slats having a width of approximately five-eighths of an inch and a thickness varying from one thirty-second to one-sixteenth of an inch, the anchorage-points being spaced one and three-fourths of an inch apart, allowing a clearance between the slats of one and one-eighth of an inch. These dimensions, however, are not essential to the production of good results.

In the preferred form of the device I employ a flexible jointless slat both ends of which are yieldingly suspended. If additional elasticity is desired, expansively-acting spiral springs may be utilized, the same being placed between the mattress and rigid frame members of the bed. As shown in Figs. 1 and 2, springs 7 are anchored upon longitudinally and laterally disposed members 8 8 and 9 9. The contractile springs supporting the metal strips at their ends permit longitudinal yielding action of the slats relatively to each other and also a rocking action of the slats relatively to each other, the loose links between the slats serving to hold the same from unduly spreading apart without preventing the same from yielding longitudinally with respect to each other and without preventing the same from rocking with respect to each other, the slats being of thin flexible strip metal, being thus capable of universal movement, rendering the entire fabric conformable to the shape of the occupant in any position. The frame supporting the strip-metal slats folds and unfolds in directions at right angles to the slats.

While I have shown and described a specific embodiment of the invention, it will be understood that departures may be made therefrom without departing from the spirit of the invention. Therefore I do not wish to be limited to the precise construction illustrated; but,

Having thus described my invention, I claim as new, and desire to secure by Letters Patent, the following:

In a bed the combination with a foldable frame, of a plurality of thin flexible strip-

metal slats, contractile springs connected with ends of said slats and with said frame affording anchorage for the thin strip-metal slats and permitting yielding longitudinal movement of each slat with respect to others and rocking movement of each slat independently of other slats, and loose links flexibly uniting the slats into a fabric and preventing undue separation between the same, the frame sup-

porting the slats being foldable and unfoldable in directions at right angles to the slats, substantially as described.

In witness whereof I hereunto subscribe my name this 20th day of November, A. D. 1903.

LEVI N. BACHAND.
